US00D838061S

(12) **United States Design Patent** (10) **Patent No.:** **US D838,061 S**
(45) **Date of Patent:** **** Jan. 8, 2019**

(54) **PET HAIR BLOWING AND SUCKING
NURSING MACHINE**

(71) **Applicant:** **NINGBO ICLIPPER ELECTRIC
APPLIANCE CO., LTD.**, Ningbo
(CN)

(72) **Inventor:** **Haoze Wu**, Ningbo (CN)

(73) **Assignee:** **NINGBO ICLIPPER ELECTRIC
APPLIANCE CO., LTD.**, Ningbo
(CN)

(**) **Term:** **15 Years**

(21) **Appl. No.:** **29/610,494**

(22) **Filed:** **Jul. 12, 2017**

(51) **LOC (11) Cl.** **30-99**

(52) **U.S. Cl.**

USPC **D30/158**; D30/199

(57) **CLAIM**

The ornamental design for pet hair blowing and sucking
nursing machine, as shown and described.

DESCRIPTION

FIG. 1 is a perspective view of my new design for a pet hair
blowing and sucking nursing machine;
FIG. 2 is a front view thereof;
FIG. 3 is a back view thereof;
FIG. 4 is a left side view thereof;
FIG. 5 is a right side view thereof;
FIG. 6 is a top plan view thereof; and,
FIG. 7 is a bottom plan view thereof.
